Charles Oscar Mueller, Inventor

UNITED STATES PATENT OFFICE.

CHARLES OSCAR MUELLER, OF NEW YORK, N. Y., ASSIGNOR TO LAMKAY & SEAMAN, INC., OF NEW YORK, N. Y., A CORPORATION OF NEW YORK.

DESIGN FOR CLOTH.

59,671.

Specification for Design.

Patented Nov. 15, 1921.

Application filed June 20, 1921. Serial No. 479,105. Term of patent 7 years.

To all whom it may concern:

Be it known that I, CHARLES O. MUELLER, a citizen of the United States, residing in the city of New York, county of New York, State of New York, have invented a new, original, and ornamental Design for Cloth, of which the following is a specification, reference being had to the accompanying drawing, forming part thereof.

The figure is a plan view of a piece of cloth embodying my new design.

I claim:

The ornamental embroidery design for cloth as shown.

Dated, New York, May 20, 1921.

CHARLES OSCAR MUELLER.
